ATTORNEY

UNITED STATES PATENT OFFICE.

ISAAC LEWENTHAL, OF NEW YORK, N. Y., ASSIGNOR TO ROYAL METAL MANUFACTURING COMPANY, OF NEW YORK, N. Y., A CORPORATION OF NEW YORK.

BELT.

SPECIFICATION forming part of Letters Patent No. 698,297, dated April 22, 1902.

Application filed December 21, 1901. Serial No. 86,736. (No model.)

To all whom it may concern:

Be it known that I, ISAAC LEWENTHAL, a citizen of the United States, and a resident of the city and county of New York, borough of Manhattan, and State of New York, (whose post-office address is 120 Walker street, in said city,) have invented certain new and useful Improvements in Belts, of which the following is a specification.

The object of my invention is to produce a belt which will embody the now prevalent "dip" or "bodice" effect—in other words, the downward extent or curve of the belt when worn—and to outline this form generally in a belt made mainly of pliable fabric, such as silk or satin, instead of leather or elastic fabric hitherto employed; and a further object of my invention is to produce a belt wherein pliable fabric, such as silk or satin or the like, is utilized to form the main portion of the belt-body, wherein the capacity of extension of the belt-body may be accommodated to wearers of varying sizes.

My invention also has for its object to generally improve the construction and general appearance of belts.

My invention therefore resides in the novel construction and combination of parts hereinafter described, and further pointed out in the claims.

In the drawings forming part of this specification, Figure 1 is a front elevation of a belt embodying my improvements. Fig. 2 is a fragmentary elevation of the belt extended out, the inner surface being exposed. Fig. 3 is a rear elevation of the same. Fig. 4 is a section on the line xx , Fig. 2, looking in the direction of the arrows, and Fig. 5 is a perspective view of one of the clips, showing the method of securing the belt-body thereto.

The belt comprises the intermediate section 1, of elastic fabric, from which extends two bands 3 4 and which are secured to the elastic fabric in any desired manner, preferably by such clips as 5 6, in which the ends of the bands and elastic fabric are secured, as shown. The bands 3 4 are each preferably made of silk or satin or some like material the character of which I do not limit myself to, and between their inner and outer

ends the fabric of the bands is so disposed as to produce by plaiting or folding a transverse fullness. At the ends the bands are each provided with clasp-sections 7 8, secured thereto by the clips 5, the latter being fixed to the sections and preferably disposed at an angle to the meeting edges 9 of the clasp-sections. The clasp-sections 7 8 are provided with the hook and eye 10 11 for uniting the ends of the bands. However, I do not limit my invention to this latter arrangement, as any form of clasp or buckle and any other disposition of the ends of the bands may be made.

At 12 is a back piece or ornament, preferably having sufficient longitudinal extension to cover the intermediate elastic section 1 and extending over to a short distance beyond the inner ends of the bands and which is preferably curved to correspond to approximately the curve of the body.

Instead of securing the back piece 12 directly to the belt-body it is provided with a plurality of loops 13, spaced apart, the ends of the loops being secured to the back piece, and the said loops are preferably connected together by a cross-bar 14, carrying a skirt-supporting hook 15.

As shown, the intermediate section 1 loosely passes under the loops, and when worn the said section is entirely hidden from view by the back piece, the latter, with the loops, providing means for the ready attachment or detachment of the belt-body to the back piece.

The construction hereinbefore described provides for readily permitting the bands or intermediate section being readily assembled or removed for repair or for other necessary causes.

Having described my invention, I claim—

1. A belt-body comprising a pair of inelastic bands having a transverse fullness, an elastic section interposed between said bands, a back piece held in place by and adapted to cover said elastic section, and a pair of clasps adapted to be secured to the free ends of said bands, the meeting edges of said clasps being disposed at such an angle as to draw the meeting edges of the belt downward forming a point.

2. A belt-body comprising a pair of inelas-

100

tic bands having a transverse fullness formed by longitudinal plaits or folds, an elastic intermediate portion interposed between said bands, and a pair of clasps adapted to be secured to the free ends of said bands, the meeting edges of said clasps being disposed at such an angle as to draw the meeting ends of the belt downward, forming a point.

3. A belt-body comprising a pair of inelastic bands having a transverse fullness formed by longitudinal plaits or folds, an elastic intermediate portion interposed between said bands, a back piece adapted to cover said

elastic section, loops carried by said back piece adapted to cover and guide said elastic section, and a pair of clasps adapted to be secured to the free ends of said bands, the meeting edges of said clasps being disposed at such an angle as to draw the meeting ends of the belt downward, forming a point.

Signed in the city, county, and State of New York this 19th day of December, 1901.

ISAAC LEWENTHAL.
